UNITED STATES PATENT OFFICE.

EDWARD BROOKS AND GEORGE S. DOYLE, OF ATLANTA, GEORGIA.

STEAM-ENGINE.

1,294,762.

Specification of Letters Patent. Patented Feb. 18, 1919.

Application filed October 4, 1917. Serial No. 194,749.

To all whom it may concern:

Be it known that we, EDWARD BROOKS and GEORGE S. DOYLE, citizens of the United States, residing at Atlanta, in the county of Fulton and State of Georgia, have invented certain new and useful Improvements in Steam-Engines, of which the following is a specification.

Our invention relates to steam engines.

10 An important object of the invention is the provision of means whereby the supply of steam to the cylinder of the engine can be properly controlled and yet introduced into the cylinder at full boiler pressure, by causing a complete valve opening movement, for each stroke of the piston.

15 A further object of the invention is to provide means to cut off the supply of steam to the cylinder, at any desired point, in the stroke of the piston.

Other objects and advantages of the invention will be apparent during the course of the following description.

20 In the accompanying drawings forming a part of this specification and in which like numerals are employed to designate like parts throughout the same,

Figure 1 is a side elevation of an engine embodying the invention,

25 Fig. 2 is a plan view of the same,

Fig. 3 is an end elevation of the same,

Fig. 4 is a side elevation of the eccentric operated means to shift the trip-cams,

Fig. 5 is an enlarged sectional view 30 through the pressure operated means for shifting an inlet or valve of the engine,

Fig. 6 is an enlarged detail section through the inlet valve,

Fig. 7 is an end elevation of the guide 35 means for the slide cam-bar,

Fig. 8 is a plan view of means for returning the slide cam-bar to the starting position, together with associated elements,

Fig. 9 is a side elevation of a plurality of 40 cranks, included in the valve shifting means,

Fig. 10 is a plan view of the same, and,

Fig. 11 is a side elevation of a manually operated lever and associated elements.

45 In the drawings, wherein for the purpose of illustration is shown a preferred embodiment of our invention, the numeral 20 designates the cylinder of the engine, having a piston (not shown) to reciprocate therein. This piston is connected with a crank shaft 50, 21, to rotate the same, as is well known.

Steam is supplied into the opposite ends

of the cylinder 20 by pressure operated apparatuses 22, and exhausted from such opposite ends by separate pressure operated apparatuses 23.

50 Each inlet apparatus comprises a shell 24, having a horizontal arm 25, leading into one end of the cylinder 20. Connected with the upper end of the shell 24 is one end of a U-coupling 26, having connection with a main steam supply pipe 27, provided with the usual throttle valve 28.

55 Each exhaust apparatus 23 comprises a shell 29, leading into one end of the cylinder 20. At one side, the shell 29 has connection 70 with an exhaust pipe 30, connected with a common exhaust pipe (not shown).

The apparatuses 22 and 23 are similar in certain respects and can be conveniently described together. In Fig. 6, each shell 24 or 75 29 is shown as provided in its upper end with a valve seat 31, having an upper portion 32 which is cylindrical and a lower tapered portion 33, decreasing in diameter downwardly. The lower portion of the 80 shell is provided with a horizontal web or partition 34, having a tubular element or gland 35, as shown. Beneath the partition 34 is a cylinder 36, receiving a piston 37, to reciprocate therein. The partition 34 is 85 provided upon its upper surface with a valve seat 38, having an upper portion 39, which is cylindrical and a lower conical portion 40, decreasing in diameter downwardly, as shown.

90 The numeral 41 designates a reciprocating valve, having an upper head 42, from which depends a tubular portion 43, of smaller diameter. The upper head 42 is provided with an upper portion 44, which is cylindrical, 95 and is adapted to fit within the upper cylindrical portion 32, and a lower tapered portion 45, adapted to fit within the lower conical portion 33. The head 42 also carries a plurality of spaced radially extending guide 100 elements or fins 46, preferably formed integral therewith, and contacting with the lower vertical portion 47 of the opening, and thus serving as guide means for the valve, when in operation. At the lower end 105 of the tubular portion 43 there is formed a valve head 48 of increased diameter, having an upper portion 49 which is cylindrical, to enter the upper cylindrical portion 39 of the opening and a lower tapered portion 50, to 110 enter the lower tapered portion 40. It is thus apparent that when the valve descends

toward its seats the steam will be practically cut off when the portions 44 and 49 of the valves enter the portions 32 and 39 of the openings, prior to the complete seating of the valve.

5 Mounted to reciprocate through the tubular portion 35 or gland, is a valve rod 51, rigidly connected with the head 42, as shown. The valve rod has grooves 52, for 10 receiving suitable packing, thus insuring a steam-tight joint with the gland 35. At its lower end, the valve rod 51 has connection with a valve lifting piston 37, to be reciprocated thereby. It is thus apparent that when 15 steam is introduced beneath the piston 37, the valve 41 will be moved to the upper unseated position, to supply or exhaust steam to or from the cylinder, as the case may be.

20 The means for supplying and exhausting steam to and from the cylinder 36, for operating each supply and exhaust valve is the same, and is shown in Fig. 5. Such means comprises a body portion or casting 53, which is rigidly secured to the cylinder 20 25 by any suitable means.

As clearly shown in Fig. 5, the casting 53 has the cylinder 36 rigidly secured to the upper end thereof. The numeral 54 designates an inlet port, adapted to be placed in 30 communication with a port 55, through the medium of a transverse port 56. The port 55 extends upwardly and leads into the lower end of the cylinder 36. The cylinder 36 is provided near its lower end with an 35 exhaust port 57, having communication with a port 58. The port 58 is adapted to have communication with a port 59, through the medium of a transverse port 60. The port 59 has communication with a pipe 61, which 40 is connected with the common exhaust pipe of the engine. Near its upper end, the cylinder 36 has an exhaust port 62, having communication with an exhaust pipe 63, which is connected with the common exhaust pipe 45 of the engine. The pipe 63 also serves to supply a suitable amount of steam from the common exhaust pipe into the upper end of the cylinder 36, thereby forming a cushion for the piston 37, as it approaches the end 50 of its up stroke and covers the port 62. When the piston approaches the end of its down stroke it covers the port 57 and the steam is entrapped in the lower end of the cylinder to provide a cushion. Arranged 55 within the port 56 to cover and uncover the same is an inlet valve 64, carried by a reciprocatory valve stem 65, which is vertically arranged, as shown. The numeral 66 designates a reciprocatory exhaust valve, arranged 60 within the port 60 to cover and uncover the same, and carried by a vertical valve stem 67. The lower ends of the valve stems 65 and 67 slidably contact with a cam lever 68, pivoted between its ends to a fixed support, as shown at 69. This cam lever

is provided at its opposite ends with anti-friction means or rollers 70 and 71, as shown.

Means are provided to oscillate the cam lever 68 and accordingly operate the valves 64 and 66, comprising a reciprocatory cam-bar 72, operating within stationary guides 73, as shown. This cam-bar 72 is provided upon its upper edge with a recess 74, having curved cam end faces 75 and 76, as shown. It is apparent that when the rollers 70 and 71 contact with the faces 75 and 76, upon the reciprocatory movement of the cam-bar 72, the cam lever 68 will be swung in opposite directions upon its pivot.

There are four cam-bars 72, corresponding in number and arrangement to the apparatuses 22 and 23, as clearly shown in Fig. 1. Arranged between the cam-bars 72 is a stationary support 77, receiving and holding a horizontal transverse shaft 78 (see Fig. 9). Pivoted upon the shaft 78 is a sleeve 79, having upstanding cranks 80 and 81, which are preferably integral therewith. Pivoted upon the shaft 78 is a sleeve 82, having upstanding and depending cranks 83 and 84, integral therewith.

As clearly shown in Figs. 1 and 9, the crank 80 has pivotal connection, at its upper end, as shown at 85, with a pitman 86, which is connected with an eccentric 88, which surrounds an eccentric 88. The eccentric is carried by the crank shaft 21. It is obvious that the eccentric 88 and associated elements serve to rock the sleeve 79. As clearly shown in Figs. 8, 9 and 10, the upper end of the crank 81 is forked for receiving therein the ends of dogs 89, such ends being pivotally connected with the forked end by means of a bolt 90 or the like.

Each dog 89 is adapted to move the adjacent upper cam-bar 72, when shifted in the direction of the arrow. It is obvious that the dogs 89 operate the cam-bars when moved in opposite directions. As clearly shown in Figs. 5 and 8, the dog 89 is provided with a tooth or lateral extension 91, to drop within a recess or notch 92, formed in the cam-bar 72. It is obvious that when the dog 89 is moved in the direction of the arrow, it will move the cam-bar 72 in the same direction. The inner end of the cam-bar 72 operates near and upon one side of a sliding trip 93, having an inclined face 94. It is thus apparent that when the tooth 91 is brought in contact with the face 94 the same extending laterally sufficiently to contact therewith, it will be elevated and moved out of the notch 92 whereby the cam-bar 72 will be released and automatically returned to its starting position, by means to be described. When the cam-bar 72 is released, and returned to the starting position, the inlet valve 41 (see Fig. 6) is returned to its seat and the supply of steam cut off from the corresponding end of the cylinder.

It is thus apparent that by the longitudinal movement or adjustment of the sliding trip 93, the time at which the supply of steam will be cut off, with respect to the extent 5 of travel of the piston, may be controlled or adjusted.

As more clearly shown in Fig. 5, the sliding trip 93 operates within guides 95, and has a depending lug 96, operating within a 10 slot 97. The lug 96 is slotted for the reception of a bolt 98, carried by a swinging crank 99, pivoted at 100 upon one end of a stationary bracket 101, as shown in Figs. 1 and 5. As clearly shown in Fig. 1, the 15 cranks 99 have pivotal connection with rods 102 and 103. The rod 102 is pivoted with its link 99 above the pivot 100 thereof, while the rod 103 is pivoted to the crank 99 beneath the pivot 100. The rods 102 and 103 20 extend forwardly for pivotal connection with a crank 104, rigidly secured to a rock-shaft 105, turned by a crank 106. This crank has pivotal connection with a link 107, pivoted to the sleeve 108 of a centrifugal 25 governor 109, driven from the crank shaft of the engine. This centrifugal governor may be of any well known or preferred type and is equipped with a safety block 110. It is thus apparent that I have provided auto- 30 matic means to shift the sliding trips 93 thereby automatically controlling the time of cut off for the supply of steam. However, it is to be understood that the invention is in no sense restricted to the employment of automatic means, as the same may be dispensed with and other means employed to shift the rods 102 and 103. As 35 illustrative of such means, the rods 102 and 103 may be pivoted to a crank 111, fixed 40 upon a rock-shaft 112. This rock-shaft is turned by a hand lever 113, carrying a latch 114, operating in proximity to a stationary quadrant 115.

The means to automatically return each 45 cam-bar 72 to the starting position, when moved therefrom and released, comprises a stationary cylinder 116 (see Fig. 8) within which is mounted to reciprocate a piston 117, having grooves 118 for the reception of 50 suitable packing. The piston 117 has connection with a rod 119, which is connected with the cam-bar 72, through the medium of a bolt 120. Pressure is supplied into the cylinder 116 through a port 121, receiving one 55 end of a pipe 112, whereby steam pressure is maintained within the cylinder 116, as will be more fully explained. As soon as the cam-bar 72, (see Fig. 1) is shifted to the left, it is obvious that the piston 117 further 60 compresses the steam within the cylinder 116, so that as soon as the cam-bar is released it is automatically returned to the right, to the starting position.

The depending crank 84 (see Figs. 1 and 65 9) is forked for receiving therein the inner

ends of a pair of links 123, pivoted therein at 124. These links are pivoted to the lower cam-bars 72, as shown at 125. The cam-bars are permanently connected with the link 94 and are shifted in both directions 70 thereby and no trip or automatic return means is employed in connection with the lower cam-bars 72. The upper crank 83, which is rigidly secured to the lower crank 84 for swinging it, has pivotal connection 75 as shown at 126 with a pitman 127, secured to an eccentric strap 128 receiving an eccentric 129. This eccentric is carried by the crank shaft 121 and is driven thereby. The eccentrics 88 and 129 are of course properly 80 timed for actuating the inlet and exhaust valves so that they operate in proper order.

As shown in Fig. 1, a pipe 130 leads into the pipe 27 above the throttle valve 28, and thereby receives steam pressure irrespective 85 of whether or not the throttle valve is opened or closed. The pipe 130 has connection with a pipe 131 having two branches 132 and 133. Each branch has connection with pipes 134, which lead into the intake 90 ports 54, as clearly shown in Fig. 5. Each branch has connection with the pipe 122.

The operation of the apparatus is as follows:

When the valve 28 is opened, steam is supplied into the U-coupling 26, and accordingly passes into the horizontal tubular arms 25, and will discharge into the cylinder of the engine, when the main valves are operated. The control valves 64 and 66 are 95 properly set and timed in their operation, so that one valve shifting piston 37 of the upper apparatus 22 is raised to open its main inlet valve 41, while the other main inlet valve is retained closed. Each inlet 100 valve 37 is moved to a complete opened position, upon each stroke of the piston, thereby supplying steam to the cylinder of the engine, at full boiler pressure. The shifting piston 37 of the exhaust apparatus 23, at the 110 opposite end of the cylinder, is raised, to unseat the main exhaust valve, and exhaust steam from the cylinder to the atmosphere. When the engine is operating, the pitman 86 and associated elements, actuate the dogs 89, 115 which in turn reciprocate the cam-bars 72, in their proper order. These cam-bars rock the cam levers 68, which in turn open and close the control valves 64 and 66. The sliding trips 93, contact with the dogs 89, and 120 release or disconnect them from the cam-bars 72, at a desired point in the stroke of the piston. The lower cam-bars 72 are reciprocated by the pitman 127 and associated elements. The cylinders 116 and associated 125 elements serve to automatically return the upper cam-bars 72 to the starting position, when moved therefrom, and released.

It is to be understood that the form of our invention herewith shown and described 130

is to be taken as a preferred example of the same, and that various changes in the shape, size, and arrangement of parts may be resorted to without departing from the spirit 5 of the invention or the scope of the subjoined claims.

Having thus described our invention, we claim:

1. In an engine of the character described; 10 a main cylinder; inlet and exhaust shells arranged near the opposite ends of the main cylinder and including valve shifting cylinders; main inlet and exhaust valves arranged within the shells; valve shifting 15 pistons mounted to reciprocate within the valve shifting cylinders and connected with the main valves; means secured to the valve shifting cylinders and having inlet and exhaust ports which lead into the same; control valves arranged within the inlet and 20 exhaust ports; pivoted cam levers to operate the control valves; inlet and exhaust valve actuating reciprocatory cam-bars to rock the cam levers; dogs to detachably engage with the inlet valve actuating cam-bars; means to trip the dogs so that they 25 release the cam-bars; automatic means to return the cam-bars to the starting position; and means to reciprocate the exhaust 30 valve actuating cam-bars.
2. In an engine of the character described; a main cylinder; inlet and exhaust shells arranged near the opposite ends of the main cylinder and including valve shifting cylinders; main inlet and exhaust valves arranged within the shells; valve shifting 35 pistons mounted to reciprocate within the valve shifting cylinders and connected with the main valves; means secured to the valve shifting cylinders and having inlet and exhaust ports which lead into the same; control valves for controlling the passage of steam through the inlet and exhaust ports; pivoted cam levers to operate the control 40 valves; inlet and exhaust valve actuating reciprocatory cam-bars having recesses provided with cam faces to contact with the ends of the cam levers to rock them; dogs to detachably engage with the inlet valve 45 actuating cam-bars to shift them in one direction; adjustable means to trip the dogs so that they release the cam-bars at a desired point in the stroke of the main piston of the engine; automatic means to return the cam-bars to the starting position includ- 50

ing pressure receiving cylinders and pistons mounted to reciprocate therein; and means to reciprocate the exhaust valve actuating cam-bars.

3. In an engine of the character described; 60 a main cylinder; inlet and exhaust shells arranged near the opposite ends of the main cylinder and including valve shifting cylinders; main inlet and exhaust valves arranged within the shells; valve shifting 65 pistons mounted to reciprocate within the valve shifting cylinders and connected with the main valves; means secured to the valve shifting cylinders and having inlet and exhaust ports which lead into the same; control valves for controlling the passage of steam through the inlet and exhaust ports; pivoted cam levers to operate the control valves; inlet and exhaust valve actuating reciprocatory cam-bars having recesses provided with cam faces to contact with the ends of the cam levers to rock them; dogs to detachably engage with the inlet valve 70 actuating cam-bars to shift them in one direction; sliding trips arranged at the sides of the cam-bars and having inclined faces to contact with the dogs and shift them out of engagement with the cam-bars; means to move the sliding trips; automatic means to return the inlet valve actuating cam-bars 75 to the starting position; and means to reciprocate the exhaust valve actuating cam-bars. 80

4. The combination with the valve of an engine, of a piston to move the same, a cylinder for receiving the piston and having inlet and exhaust ports, inlet and exhaust valves for said ports having stems, a pivoted cam lever arranged to contact with the valve stems, a reciprocatory cam-bar having cam faces to contact with the ends of the pivoted cam lever and provided with a notch, a reciprocatory slide cam arranged near and upon one side of the cam-bar and provided with an inclined face, a dog having a laterally extending head to contact with the cam-bar and slide cam, and means to move the dog. 95

In testimony whereof we affix our signatures in presence of two witnesses.
